UNITED STATES PATENT OFFICE.

JAMES T. HALL, OF CHICAGO, ILLINOIS.

CATTLE-GUARD.

SPECIFICATION forming part of Letters Patent No. 512,509, dated January 9, 1894.

Application filed July 14, 1890. Serial No. 358,719. (No model.)

To all whom it may concern:

Be it known that I, JAMES T. HALL, a citizen of the United States, residing at Chicago, in the county of Cook and State of Illinois, have invented certain new and useful Improvements in Surface-Railway Cattle-Guards, of which the following is a specification, reference being had therein to the accompanying drawings.

10 This invention relates to new and useful improvements in railway surface cattle guards; and the invention consists in the peculiar construction of a metallic surface guard whereby the cost of such cattle guards is greatly reduced, while at the same time the footing of 15 stock is effectually destroyed all as more fully hereinafter described and claimed.

In the drawings which accompany this specification, Figure 1 is a perspective view 20 of my improved cattle guard. Fig. 2 is a longitudinal section thereof on line xx in Fig. 1. Fig. 3 is a cross-section through one section of the guard. Fig. 4 is an enlarged perspective view of one corner of the guard.

25 My improved cattle guard is composed of three or more plates A, of sheet metal of suitable length and width to form a complete section of cattle guard, each plate being apertured by means of punches and dies or any 30 other suitable method, so as to produce an upward displacement of the metal from each aperture. The size and form of the aperture B ought to be large enough to prevent the feet of men or animals from being caught fast, 35 and preferably so as to avoid sharp corners on the raised portions C which would injure the foot were it brought in contact therewith. The latter form upwardly presenting edges to destroy the footing for animals, without 40 injuring the same and by arranging them in the longitudinal direction of the guard they are less liable to form an obstruction for trailing objects from a train.

In order to destroy the footing more effect- 45 ually, I avoid regularity by causing the raised portions to be alternate or otherwise in irregular order, or by using two or more different dies for producing different forms of raised portions in each plate, as shown.

50 To raise the guard from the ties on which it is supported so that a sounding diaphragm may be formed which will vibrate or produce

a cracking noise when weight is placed thereon and also to increase the bearing strength of my cattle guard, I form an angle or flange 55 around the edges of the plates, preferably by bending down the edges at an incline, say forty-five degrees more or less. These flanges form an important element of security to the cattle guard and also permit of fastening it 60 firmly to the ties by a few spikes driven on the edges of the plates into the ties. They also form an element of economy as they shorten the height of the raised portion required to reach the level of the track, and 65 thereby diminish the thickness of plate otherwise required to make the raised portions stiff enough.

Long experience in cattle guards has demonstrated to me the absolute necessity of having no direct obstructing points exposed, and therefore, I construct all the parts of my guard in a manner that will not permit any dragging appendage of a railway train, to be obstructed by any upturned part of my guard, 75 but will in all cases permit a free passage of the hanging appendage without injury to the same or the cattle guard.

It is obvious that the longitudinal edges of the plates may be bent to any plane as the 80 necessity for the incline exists only for the front and rear edges of the guard.

What I claim as my invention is—

1. A metal cattle guard section consisting of a metal plate having raised portions adapted 85 to destroy the footing and supported above the ties by depressed flanges around its outer edges, substantially as described.

2. A metallic cattle guard section consisting of a metallic plate having raised portions with 90 blunt upper ends projecting from its upper surface arranged with their sides parallel with the longitudinal edges of the plate and in lateral rows each projection being in a line with the center of the space between the adjacent 95 row of teeth and depressed flanges formed upon the edges of the plate, substantially as described.

3. A cattle guard section consisting of a metallic plate having a series of upwardly extending teeth with blunt upper edges struck up from the metal of the plate, substantially 100 as described.

4. A cattle guard section consisting of a sin-

gle plate beset with longitudinal projecting edges cut from the metal thereof, substantially as described.

5. A cattle guard section consisting of a base adapted to be supported above the ties and a series of upwardly projecting pointless fin-like projections on the base arranged adjacent to each other, substantially as described.

6. In a cattle guard, a section composed of a 10 metallic plate having portions thereof bent down to form supports, and a series of upwardly projecting flanges struck up from the metal of the plate, substantially as described.

7. A cattle guard section composed of a single metallic plate with depending edge flanges, 15 substantially as described.

8. A cattle guard section consisting of a base and a series of separated upwardly projecting straight plates thereon formed with pointless upper edges, substantially as described. 20

9. A cattle guard section consisting of a series of short vertical plates having pointless upper edges separated from each other and secured in place their edges being presented upwardly, substantially as described. 25

In testimony whereof I affix my signature, in presence of two witnesses, this 12th day of June, 1890.

JAMES T. HALL.
